BABY HOLDING BELT FOR USE IN A SHOPPING CART

Richard L. Kausen and Judith L. Kausen, both of 20810 Avenue 204, Lindsay, Calif. 93247

Filed May 4, 1967, Ser. No. 6,950

Term of patent 14 years

(Cl. D15—1)

FIG. 1 is a top plan view of a baby holding belt for use in a shopping cart showing our new design.

FIG. 2 is a bottom plan view thereof.

FIG. 3 is a front elevation thereof.

FIG. 4 is a rear elevation thereof.

FIG. 5 is a side elevation thereof.

FIG. 6 is an elevational view of the opposite side from the side shown in FIG. 5.

FIG. 7 is a perspective view thereof.

We claim:

The ornamental design for a baby holding belt for use in a shopping cart, as shown.
